CLAIM

The ornamental design for a land clearing apparatus for forestry, as shown and described.

DESCRIPTION

FIG. 1 is a top perspective view of a land clearing apparatus for forestry showing our new design;

FIG. 2 is a left side view thereof;

FIG. 3 is a right side view thereof;

FIG. 4 is a top view thereof;

FIG. 5 is a rear view thereof;

FIG. 6 is an underside perspective view thereof; and,

FIG. 7 is a rear perspective view thereof.

The broken lines in the drawings illustrate portions of the land clearing apparatus for forestry, which form no part of the claimed design.
